AUTOMATIC MAGAZINE FEED SOLID FUEL HEATER

William T. Bradbury, Oreland, Pa., and Cecil E. Chesser and Herman F. Lieber, Newark, Ohio, assignors to Newark Stove Company, Newark, Ohio, a corporation of Ohio

Application January 21, 1942, Serial No. 427,534

3 Claims. (Cl. 126—77)

Our invention relates to stoves, heaters and furnaces, being adaptable for space heaters as well as for hot air furnaces or other heating appliances, including water or other liquid heaters. More particularly, our invention has to do with a type of heating device which, so far as its general design is concerned, has been known for a long time, being of a type variously referred to in the art as magazine stoves, base burners, self-stokers, etc.

Broadly considered, the type of heater referred to consists of a magazine for solid fuel, such as coal, sawdust, briquettes, etc., into the top of which the fuel is fed at intervals, a grate being disposed under said magazine and an outer wall spaced from said magazine to form an annular combustion chamber around the magazine. The device may be circular, square, or otherwise shaped in its general cross-sectional contour. In operation, the fuel is disposed within the magazine and rests on the grate, being coked as it approaches the lower portion of the magazine, and gaseous combustion taking place mainly in the space above the fuel bed lying on the grate and within the annular combustion chamber.

We have made certain improvements in the type of device broadly described above which we believe to be new and which substantially improve the operating efficiency of the device, this being one of the principal objects of our invention.

Another object of our invention is to provide, in a device of the type described, an improved arrangement for feeding secondary air into the gaseous products of combustion adjacent the base of the combustion chamber, whereby complete combustion will occur in the combustion chamber, thus tending to produce maximum heating efficiency. Thus, according to our invention, substantially no combustion is permitted to occur in the stack.

Still another object is to provide a device of the type referred to which is so designed that it is simple and inexpensive to construct, substantially fool-proof in operation, and in general entirely satisfactory for the purposes desired.

Various other objects and advances will no doubt suggest themselves to those skilled in the art as the description proceeds.

Referring now to the drawing forming a part of this specification and illustrating a preferred embodiment of our invention,

The single figure is a vertical sectional view of a heater embodying our invention.

In the drawing, the numeral 10 indicates a casing which, in the embodiment shown, happens to be cylindrical, but may be square or otherwise shaped in cross section. Said casing has a side wall 11 and a top wall 12. A suitable base

15 is provided over which is disposed an ash pit portion 16, an access door 17 being provided for the ash pit in which is disposed an ash pan 18. Secured within the side wall 11 of the casing, 5 as by means of brackets 19 or other suitable means, is a heat resistant lining 20 of cast iron, or other suitable heat resistant material. The lining 20 extends from a portion approximately midway between the grate 22 and the top of the 10 stove to the grate itself, the grate being supported on a flange 23 formed on the lower edge of the lining 20 or on suitable lugs formed thereon. The grate may be of any suitable shape; in the embodiment shown it consists of a substantially horizontal portion 24 and an upwardly and outwardly extending peripheral portion 25, the grate being latticed to permit passage of primary air into the fuel bed lying thereon. (The upper outline of the fuel bed is indicated by the dotted lines 21.) A shaker arm 26 connected to the grate extends forwardly toward door 17.

It will be noted that the lower portion of the heat resistant lining 20 tapers to form a substantially conical fuel retaining portion 30.

25 Arranged within the casing 10 and secured as by welding to the top wall 12 thereof is a substantially cylindrical magazine portion 32 which is associated with a downwardly and outwardly tapering magazine portion 33 formed of heat 30 resistant material, such as cast iron, fire clay, or other suitable material. This conical portion of the magazine may be supported in any suitable manner.

The wall 11 is provided with a flue outlet 45, and a substantially horizontal baffle element 46 is arranged below the outlet 45 and within the space between the magazine and the wall 11. This baffle may extend throughout substantially the rear half of the combustion space so that the combustion gases are forced forwardly of the device in a more or less tortuous path instead of being sucked toward the outlet in a more or less direct path. In this way the entire casing is substantially uniformly heated, thus providing efficient heat exchange.

45 A pivoted lid 47 is provided for the introduction of fuel into the magazine. The upper portion of the magazine is also provided with a gas relief damper 50 which may be controlled manually, as by means of a lever 51, or may, if desirable, be connected by a suitable linkage with the lid 47, so that when the lid is opened for refueling, any gas within the magazine will immediately be automatically discharged to the stack rather than into the room, thereby also preventing spontaneous flashing of such gas within the magazine. Such connections between the gas relief damper and the lid are old in devices of this type.

50 A damper 55 is provided for the control of primary air through a port 56 in the casing below the

grate, said damper 55 being hingedly mounted on a pintle 58. The damper preferably carries an ear 60 which extends more or less horizontally toward the casing. A rod 62 is mounted on the casing by means of a bracket 63 secured to the upper portion thereof, said rod slidably extending through one or more ears 64 and the lower portion thereof impinging on the ear 60 of the damper. The rod is threaded into the bracket 63 and has attached to the upper portion thereof an adjustment handle 66, one end of which serves as a pointer cooperating with a dial which may be formed on or secured to the upper face of the bracket 63.

The arrangement just described serves as an automatic thermostatic control for the damper 55 in the following manner: When the stove is cold, the handle 66 may be rotated to open the damper, if it is not already open, by reason of the threaded arrangement of the rod through its support 63, the screwing down of the rod bearing against the ear 60 and thus rocking the damper in a counter-clockwise direction to open position. As the casing 10 heats up and expands the rod will naturally be raised by its support 63, thus releasing pressure on the ear 60 and permitting the damper gradually to close.

Obviously, by a slight modification, the rod may be arranged to actuate a flue damper instead of a draft door, as shown.

It is believed from the foregoing that the advantages of our improved construction will be clearly apparent. The downwardly tapered conical lower portion 33 of the magazine permits the fuel to expand as it cokes thus preventing "arching" thereof, which is a serious disadvantage in many devices of this type. The introduction of heated air under pressure into the upwardly rising stream of combustible gas distilled from the fuel bed adds greatly to the efficiency of combustion within the heater itself and substantially prevents the escape of any combustibles in the stack.

A plurality of relatively small openings or ports are provided in the lining 20, preferably at comparatively short equi-spaced intervals. Air flows around the outside of the liner 20, being heated as it contacts the fire box portion 30, issuing through the ports P in relatively small and closely spaced jets into the gases of combustion between the conical element 33 and the liner 20.

Inasmuch as the device is designed to operate at best efficiency with the solid fuel bridging the space between the lower edge of the conical member 33 and the liner 20 as indicated by the dotted lines 27, it will be seen that secondary air is introduced at or near the base of the column of combustible gas, i. e., near the level at which the latter issues from the solid fuel. In this way the secondary air is thoroughly commingled with such gases, greatly enhancing the efficiency of combustion.

The cylindrical portion 33a is of the same or similar heat resistant material as the portion 33 and may be either integral or separately formed, as shown. The sheet metal magazine element 32' extends from the top wall 12 of the casing around the outside of the portion 33a and is seated on a shoulder S formed on the member 33.

As stated, our invention is applicable either to radiant stoves, circulating room heaters, liquid heaters, or furnaces. In the case of circulators or furnaces, there will, of course, be an additional casing outside of the casing 10 for the passage of air.

Various changes coming within the spirit of our invention will become apparent to those skilled in the art, and hence we do not wish to be limited to the specific form shown or uses mentioned, except to the extent indicated in the appended claims.

We claim:

1. In a space heater, a heater jacket comprising a cylindrical enclosure affording a combustion chamber and an air supply chamber, a plurality of support element intervening said chambers for supporting a grate centrally thereof, a cylindrical lining member having radially spaced supporting lugs and comprising a portion parallelly spaced from said jacket and a portion converging conically and also supported upon said elements, a magazine and hopper structure comprising a cylindrical portion and flared skirting portion, the lowermost extremity of which rests upon said lugs and is spaced so as to provide a restricted gas passageway with said parallelly spaced portion of said cylindrical lining, said lining having a plurality of radial openings for communicating a supplemental oxygen supply from the space between itself and said jacket to said constricted passageway, and draft flue means communicating with the space between said magazine and hopper structure and said jacket for drawing off the gaseous products of combustion after they have passed said constricted passageway.

2. In a space heater, a metallic enclosure jacket affording a combustion chamber and an air supply chamber, means for supporting a fire bed grate comprising a plurality of secured elements intervening said chambers, a magazine and hopper structure extending longitudinally of said combustion chamber and comprising a flared skirting portion, a fire lining element having a section parallelly spaced from said jacket and a section converging conically dependent therefrom and resting upon said secured elements, said liner having means extending therefrom for supporting the skirted portion of said magazine and hopper structure in spaced relationship with said parallel portion of the lining to provide a gas passageway and a plurality of closely spaced secondary draft supply passageways for communicating between the space formed between the jacket and the parallel portion of said lining with said gas passageway whereby complete combustion of gaseous combustibles passing through said passageway is assured.

3. In a space heater, a metallic heater jacket comprising a cylindrical enclosure affording a combustion chamber and an air supply chamber, a cylindrical lining member having circumferentially spaced supporting lugs and comprising a section parallelly disposed with respect to said jacket and a section converging conically, a fuel hopper comprising a cylindrical portion and a flared skirt portion extending through said combustion chamber, said hopper being mounted upon said supporting lugs and having its lowermost extremity spaced from said lining member to provide a restricted passageway, said liner having a plurality of closely spaced openings in that portion thereof adjacent said restricted passageway, so as to support substantially complete combustion of escaping gases drawn through said restricted passageway.
